(57) **CLAIM**

The ornamental design for a display screen or a portion thereof with a graphical user interface as shown and described.

DESCRIPTION

This application is related to the following commonly owned co-pending patent applications: U.S. application Ser. No. 29/865,082, entitled “Display Screen or Portion Thereof with a Graphical User Interface;”; U.S. application Ser. No. 29/865,084, entitled “Display Screen or Portion Thereof with a Graphical User Interface;”; U.S. application Ser. No. 29/865,085, entitled “Display Screen or Portion Thereof with a Graphical User Interface;”; and U.S. application Ser. No. 29/865,087, entitled “Display Screen or Portion Thereof with a Graphical User Interface;”.

The FIGURE is a front view of a display screen or portion thereof with a graphical user interface showing our new design.

The dashed broken line perimeter in the drawing illustrates a display screen or portion thereof and forms no part of the claimed design.
